Patented Aug. 28, 1928.

UNITED STATES PATENT OFFICE.

RICHARD M. JUDD, ERNEST C. TAYLOR, AND JOSEPH WORTH, OF DOWAGIAC, MICHIGAN, ASSIGNEES TO PREMIER WARM AIR HEATER COMPANY, OF DOWAGIAC, MICHIGAN, A CORPORATION OF MICHIGAN.

CASING HANGER.

Application filed February 13, 1928. Serial No. 254,110.

This invention relates generally to warm air furnaces and refers particularly to means for hanging inner liners to the outer casings of such furnaces.

5 The primary object of the present invention is to provide a casing hanger for supporting and spacing an inner liner from its outer casing and to so construct the hanger that it will withstand undue strains 10 and stresses.

With these and other objects in view the invention resides in certain novel features of construction, combinations and arrangements 15 of parts as will be hereinafter more fully described and particularly pointed out in the appended claims.

In the drawings:

Figure 1 is a view showing a hanger applied to a furnace casing and inner liner in accordance with the present invention;

Figure 2 is a detail view of the hanger;

Figure 3 is a vertical section of the hanger with the casing and inner liner in operative position.

25 In the accompanying drawings wherein like characters of reference designate like parts, the numeral 1 indicates a warm air furnace, 2 the outer casing therefor and 3 an inner liner spaced from the casing so as to provide an insulating air space. In 30 order to adequately support the inner liner 3 and space the same from the casing 2, there are provided hangers 4 positioned adjacent the bottom of the liner and casing spreaders 5 located at the top portions 35 thereof.

As shown, the outer casing 2 is composed of upper and lower sections 6 and 7, respectively having a central casing ring 8 interposed therebetween which supports the inner liner hangers 4. These hangers are adapted to be hung at spaced intervals from the casing ring 8 in sufficient quantities to adequately support the inner liner and uniformly space the same from the casing.

45 Each hanger consists of an elongated body 9 which, when placed in position, lies in close proximity to the inner face of the casing 2. As shown, the upper end of the body 50 9 terminates in a hooked portion 10 which is adapted to be hung over the central casing ring 8 for supporting the hanger in place.

The lower end of the hanger is provided with an inwardly extending diagonal portion 11 having an upwardly extending flange 12 cooperating therewith to form a wedge shape opening adapted to receive the lower edge of the inner liner 3. The flange 12 is provided with a closed return bent portion 13 which is in turn provided with a laterally projecting flange 14 terminating in substantially the plane of the elongated body portion 9 and adapted to abut the inner face of the casing 7 for spacing the inner liner 3 from the casing.

With the inner liner in position as shown in Figure 1 it will be apparent that any undue weight or strain imposed upon the lower end of the hanger will not effect a separation of the parts forming the wedge shape opening but will merely tend to force the portions 11 and 12 into firmer contact with the portions 13 and 14 and to force the lateral flange 14 into firmer engagement with the inner face of the casing 7. Thus it will be apparent that the hanger of the present invention presents a strong and durable construction adapted to adequately withstand the weight imposed thereon by 80 an inner liner.

While it is believed that from the foregoing description, the nature and advantage of our invention will be readily apparent, we desire to have it understood that we do not 85 limit ourselves to the specific construction herein shown and described and that such changes may be resorted to when desired as fall within the scope of what is claimed.

What we claim as our invention is:

1. A hanger for the inner liner of a furnace casing comprising a body provided with an inwardly offset portion having a flange projecting upwardly therefrom and cooperating therewith to form an opening adapted to receive the lower edge of the inner liner, said upwardly projecting flange being provided with a return bent portion having a laterally projecting flange adapted to engage the casing for spacing the inner liner from said casing.

2. A hanger for the inner liner of a furnace casing comprising a body provided with a laterally offset portion adapted to receive the lower edge of the inner liner, the lower end portion of said hanger ex-

tending laterally from said offset portion and being adapted to space the inner liner from the casing.

3. A hanger for the inner liner of a furnace casing comprising an elongated body adapted to engage the inner face of said casing provided with an inwardly extending offset portion adapted to receive the lower edge of the inner liner, the lower end portion of said hanger extending laterally outward from said inwardly offset portion and being adapted to engage the inner face of the casing for spacing the inner liner therefrom.
4. A hanger for the inner liner of a furnace casing having an elongated body adapted to engage the inner face of said casing and provided with an inwardly extending diagonal portion having an upwardly extending flange cooperating therewith to form an opening adapted to receive the lower edge of the inner liner, said upwardly extending flange being provided with a return bent portion having an outwardly projecting
5. A hanger for the inner liner of a furnace casing having an elongated body adapted to engage the inner face of said casing and provided with an inwardly extending diagonal portion having an upwardly extending flange cooperating therewith to form a wedge-shaped opening adapted to receive the lower edge of the inner liner, said upwardly extending flange being provided with a return bent portion having a horizontal flange projecting outwardly below the aforesaid diagonal portion and terminating in substantially the plane of the elongated body for spacing the inner liner from the casing.

flange adapted to engage the inner face of the casing for spacing the inner liner from said casing.

5. A hanger for the inner liner of a furnace casing having an elongated body adapted to engage the inner face of said casing and provided with an inwardly extending diagonal portion having an upwardly extending flange cooperating therewith to form a wedge-shaped opening adapted to receive the lower edge of the inner liner, said upwardly extending flange being provided with a return bent portion having a horizontal flange projecting outwardly below the aforesaid diagonal portion and terminating in substantially the plane of the elongated body for spacing the inner liner from the casing.

In testimony whereof we affix our signatures.

RICHARD M. JUDD.
ERNEST C. TAYLOR.
JOSEPH WORTH.
